UNITED STATES PATENT OFFICE.

DWIGHT F. KILGOUR, OF LEXINGTON, MASSACHUSETTS.

BOILER-SETTING.

No. 909,805.

Specification of Letters Patent.

Patented Jan. 12, 1909.

Application filed April 1, 1908. Serial No. 424,500.

To all whom it may concern:

Be it known that I, DWIGHT F. KILGOUR, a citizen of the United States, and a resident of Lexington, in the county of Middlesex and 5 State of Massachusetts, have invented an Improvement in Boiler-Settings, of which the following description, in connection with the accompanying drawings, is a specification, like letters on the drawings representing 10 like parts.

My invention relates to an improved setting for boilers or other generators or apparatus requiring to be heated, the aim of my invention being to provide a setting which 15 will improve the combustion attainable, not only for the purpose of providing a higher heating effect but also to eliminate objectionable smoke in whole or in part.

My invention consists in various features 20 of construction novel in themselves and in combination, which will be best understood from a description of one embodiment of the invention.

In the accompanying drawings: Figure 1, 25 in vertical, longitudinal section, shows one embodiment of my invention, the boiler being shown in elevation; Fig. 2 is a vertical, transverse section on the dotted line 2—2 of Fig. 1, looking to the right; and Fig. 3, 30 a similar section, on the dotted line 3—3 of Fig. 1, also looking to the right; Fig. 4 is an enlarged detail of the jet pipe arranged in the bridge wall.

In the particular embodiment of my invention selected for illustration herein and 35 shown in the drawing, the boiler indicated at B may be of any suitable or desired type or construction. In the present instance it is a fire tube boiler of usual type, having 40 the up-take b at its front end and in communication with the stack or chimney.

The boiler is supported and surrounded by the usual, double walls c, of brick or other material as may be desired, and which do not 45 in the present instance constitute any particular part of my invention except in so far as they are employed in combination with other and special features to be described.

The fire door is at the front of the boiler 50 and marked d, the same communicating directly with the fire chamber D containing a usual or desired grate d'. Beneath the grate is the usual ash pit d², provided at its front end with the ash door d².

55 At the rear end of the fire chamber and of the grate therein is the bridge wall e of usual

height and not unlike in construction and arrangement the usual bridge wall, other than in the present instance the same is made of sufficient depth from front to rear to permit of the arrangement of a transverse vertical air duct e'. This air duct, at its lower end, communicates through a forwardly extended passage e² with the ash pit d² and at its upper end said air duct is closed but provided with one or more, preferably a plurality of outlets shown as twyers e³, rearwardly directed and provided as indicated in Fig. 3 each with a series of small apertures e⁴.

In the bottom of the air duct e' I have arranged a steam jet pipe f, controlled exteriorly of the setting (see Fig. 3) by a valve f' and provided along its upper edge with a series of perforations f² through which live steam, taken from a suitable source, may be 70 projected up through the air duct e', drawing with it more or less heated air from the ash pit d², the combined air and steam being 75 projected rearward from the twyers in the direction in which the products of combustion 80 from the fire chamber D are flowing.

At the rear of the bridge wall e and at a suitable distance therefrom is a solid wall h, closely fitting the under side of the boiler and provided at or near its bottom with an 85 opening preferably of the size and communicating with a rearwardly extended combustion chamber H. This combustion chamber comprises side walls set in from the main walls of the setting, said chamber being 90 preferably of general horse shoe shape, with a flat wall at the bottom, and is made preferably slightly flaring and the axis of said chamber is inclined slightly downward toward the rear, as best indicated in Figs. 1 95 and 2. This combustion chamber while laterally contracted to collect and concentrate 100 the gases from the sides of the fire chamber and mixing chamber must not be so small as to offer any obstruction to the flow of gases therethrough nor should it be obstructed; on the contrary, it should be made of such dimensions and so free and open as to facilitate the draft and the resultant flow of gases and to this end, for the best results, 105 should present an unobstructed cross-sectional area of about one and one-half times that of the combined area of the tubes in the boiler. These relative dimensions will apply to ordinary conditions but, obviously, will 110 be varied as the conditions vary.

In practice the fuel, fired upon the grate

d', gives off its products of combustion which flow rearward over the bridge wall, as indicated by the arrows in Fig. 1, and encountering the solid wall *h* are deflected downward behind the bridge wall to or near the bottom of the setting thus concentrating the gases from the top to bottom or vertically. As they pass the bridge wall the products of combustion are mixed with the air and steam projected into the vertical mixing chamber, here marked *F*, and located behind the bridge wall, passing or being deflected downward therethrough, thence rearward through the combustion chamber *H*, which collects and draws in the gases at the sides, concentrating all the gases laterally, the same passing thence through the larger chamber *I* to and behind the rear end of the boiler returning through the tubes in the latter to the front, thence upward through the up-take to the stack. By this arrangement the products of combustion are, so to speak, distilled off in the fire chamber and as they pass over the bridge wall, and are then at and in the immediate rear of the latter mixed with the oxygen and hydrogen from the heated air and steam projected into the gases, becoming thoroughly mixed therewith in the mixing chamber *F*, the final combustion taking place in the combustion chamber *H*. The effect of the combustion is to heat the walls of the combustion chamber to an intense and practically white heat of incandescence, so that the combustion occurring therein amounts almost to a continuous explosion, so to speak, effecting in actual practice practically complete combustion, so complete as to be at nearly all times perfectly transparent and even at times of firing only slightly discolored.

If the combustion chamber *H* were obstructed, as has been attempted heretofore, by the introduction of steam and air mixing devices at the point, the flow of the gases would be retarded, and the furnace choked resulting in an explosion, which would throw the fire out at the front, and even so without proper combustion. In the present instance, however, sufficient time is given after the products of combustion pass the bridge wall to permit the oxygen and hydrogen supplied by the air and steam to become thoroughly mixed therewith and they will have reached the combustion chamber by the time the actual union or combustion takes place, so that really the most intense heat is in the combustion chamber *H*. This renders the combustion itself substantially perfect to eliminate smoke, and the intense heat resulting therefrom, which would otherwise scorch the boiler, is prevented from so doing by the distance separating the top wall of the combustion chamber from the under side of the boiler, there being, so to speak, a dead space surrounding the combustion

chamber which retains sufficient heat to avoid chilling the boiler but prevents any excessive heat thereat.

Tests show that the injurious expansion and contraction of boilers at this point is by my invention almost entirely eliminated and the heat rendered almost substantially uniform from front to rear of the boiler. The complete combustion also eliminates the deposit of ash and soot in the tubes and other passages of the setting.

By inclining the axis of the combustion chamber *H* downwardly I insure such contact of the gasses passing therethrough with the heated walls of the chamber as will effect perfect combustion. If the upper wall were not deflected downward some of the gases might creep along and make their exit without proper combustion.

Most furnaces, particularly those used in connection with medium size and larger boilers, are provided with at least two firing doors, because the widths of the grate areas and the firing chambers are such as to make it impossible properly to fire the entire widths thereof through one centrally located door. With such wide fire chambers, and particularly when two doors are employed, it becomes necessary practically to fire one side of the grate at a time, and it has been found in practice that the products of combustion rising from the fuel near the sides of the fire chamber continue to travel throughout the succeeding chambers close to the sides thereof, there being nothing to compel the commingling of the side and center gases. In fact, the depending, semi-circular cross sections of the boiler, presenting the upwardly extended, tapering wing chambers, furnish the very construction which tends to retain the side gases next to the sides of the chambers and passages throughout their course through the boiler setting, and these are the products of combustion which it is found most difficult properly to consume. My invention handles these in a highly effective and efficient manner. Referring first to Figs. 1 and 3, the products of combustion rising from the fuel on the grate pass in a wide sheet rearward over the bridge wall, the products from the front and rear of the fire chamber being concentrated vertically, that is, from top to bottom, as they pass over the bridge wall, beyond which they are deflected downward and thereby forced vertically, so to speak, to mix and combine. As stated, however, the combustion chamber *H* is contracted laterally, which causes the gases or products of combustion which have been flattened or concentrated from top to bottom now to be brought together from the sides into what might roughly be termed a vertical sheet or film, in order to pass through the combustion chamber *H*, so that the products of com-

bustion are first concentrated vertically, then deflected, and, finally, concentrated laterally, with the result that they are thoroughly commingled to produce a volume of gas which is substantially uniform throughout. The vertical deflection of the gases in following the course described, in connection with this lateral concentration, has proven highly efficient as a means for concentrating the gases. It is doubtful if this alone would produce the best results, and therefore my invention comprehends means such as described for projecting air and steam into the products of combustion as they pass over the bridge wall, so that the concentration and mixing of the products is effected in the presence of and is assisted and promoted by the air and steam injected thereto, resulting in a complete and uniform mixture of the products themselves and the air and steam that is admitted thereto, all tending to produce the most efficient heating effect and the most complete elimination of smoke. Quite important, however, is the fact that all this is obtained by the combination and arrangement of entirely open flues, passages or chambers, which offer no obstruction to the draft and therefore do not retard the firing of the boiler. I am aware that it has been attempted to force the mixture of the gases and promote combustion thereof by introducing in the path of the same brick checkerwork and the like, intended to break up the gases, but my invention aims to eliminate all such obstructions and to produce the desired result by a proper arrangement and relationship of open tubes and chambers, such as herein shown and referred to in the claims. Furthermore, that portion of the boiler which is most likely to be burned or scorched is just back of the bridge wall which, by my invention, as will appear from Fig. 1, is completely protected by the depending wall h , which completely bars the flow of the products of combustion at that point and deflects them downward to and through the combustion chamber and forces the combustion lower and more to the rear, thereby equalizing the heating effect as compared with what has heretofore been possible; that is to say, that part of the boiler immediately in the rear of the bridge wall which has heretofore been overheated, is, by my invention, protected; while the extreme rear end of the boiler, which heretofore has lacked of sufficient heat, is, by my invention, supplied with increased heat because of the combustion which is forced in the combustion chamber H and in the rear thereof, this combustion being of the gases which heretofore have gone off unconsumed. The result is a uniformity of heating effect, which promotes generation of steam and the elimination of smoke. It will be observed that the dead space above the combustion cham-

ber H and between the latter and the boiler is closed at the front, to prevent the products of combustion from projecting thereinto and by being pocketed scorch the boiler, but is open at the rear end and where it may receive, so to speak, the heat by radiation or reflex action, all tending to equalize the heating effect throughout the entire length of the boiler.

In the upper part of the mixing chamber F I have shown a pinhole P , to permit observation of the combustion within the mixing chamber when desired.

Claim:

1. A setting for a boiler comprising a fire-box having a bridge wall and a downwardly extended deflecting wall positioned in the rear of said bridge wall to leave between them a mixing chamber down which the products of combustion are bent or deflected, in combination with a single combustion chamber of substantial length and constituting a single outlet-passage for the mixing-chamber, said combustion chamber outlet-passage at its entrance end being substantially narrower than said mixing chamber and unobstructed, thereby to draw laterally together and enforce intermingling of the products of combustion flowing from opposite side portions of said fire-box.

2. A setting for a boiler comprising a fire-box having a bridge wall and a downwardly extended deflecting wall positioned in the rear of said bridge wall to leave between them a mixing chamber down which the products of combustion are bent or deflected, in combination with a single combustion chamber of substantial length and constituting a single outlet-passage for the mixing-chamber, said combustion chamber outlet-passage at its entrance end being substantially narrower than said mixing chamber and unobstructed, thereby to draw laterally together and enforce intermingling of the products of combustion flowing from opposite side portions of said fire-box, and means to introduce oxygen contiguous to said bridge wall.

3. A setting for a boiler comprising a fire-box having a bridge wall and a downwardly extended deflecting wall positioned in the rear of said bridge wall to leave between them a mixing chamber down which the products of combustion are bent or deflected, in combination with a single combustion chamber of substantial length having its axis inclined and constituting a single outlet-passage for the mixing-chamber, said combustion chamber outlet-passage at its entrance end being substantially narrower than said mixing chamber and unobstructed, thereby to draw laterally together and enforce intermingling of the products of combustion flowing from opposite side portions of said fire-box.

4. A setting for a boiler comprising a fire-box having a bridge wall and a downwardly extended deflecting wall positioned in the rear of said bridge wall to leave between them a mixing chamber down which the products of combustion are bent or deflected, in combination with a single flaring combustion chamber of substantial length and constituting a single outlet-passage for the mixing-chamber, said combustion chamber outlet-passage at its entrance end being substantially narrower than said mixing chamber and unobstructed, thereby to draw laterally together and enforce intermingling of the products of combustion flowing from opposite side portions of said fire-box.

5. A setting for a boiler comprising a fire-box having a bridge wall and a downwardly extended deflecting wall positioned in the rear of said bridge wall to leave between them a mixing chamber down which the

products of combustion are bent or deflected, in combination with a single combustion chamber of substantial length and constituting a single outlet-passage for the mixing-chamber, said combustion chamber outlet-passage at its entrance end being substantially narrower than said mixing chamber and unobstructed, thereby to draw laterally together and enforce intermingling of the products of combustion flowing from opposite side portions of said fire-box, the top wall of said combustion chamber being separated from a boiler above it to leave an open dead chamber. 35

In testimony whereof, I have signed my name to this specification, in the presence of two subscribing witnesses.
